UNITED STATES PATENT OFFICE

152,797

DESIGN FOR A NECKLACE OR SIMILAR
ARTICLE

Adolph Katz, Providence, R. I., assignor to Coro,
Inc., New York, N. Y., a corporation of New
York

Application December 3, 1948, Serial No. 149,951

Term of patent 7 years

(Cl. D45—16)

To all whom it may concern:

Be it known that I, Adolph Katz, a citizen of the United States of America, residing in Providence, county of Providence, and State of Rhode Island, have invented a new, original, and ornamental Design for a Necklace or Similar Article, of which the following is a specification, reference being had to the accompanying drawing, forming part thereof.

Fig. 1 is a plan view of a necklace or similar article showing my new design.

Fig. 2 is an edge view thereof.

The links shown in full lines are repeated throughout the length of the necklace as indicated by the broken line disclosure.

I claim:

The ornamental design for a necklace or sim-

ilar article, substantially as shown and described.

ADOLPH KATZ.
